United States Patent Office.

IMPROVED SCISSORS SHARPENER.

JAMES J. TOBEY, OF BOSTON, MASSACHUSETTS.

Letters Patent No. 59,785, dated November 20, 1866.

SPECIFICATION.

TO ALL WHOM IT MAY CONCERN:

Be it known that I, JAMES J. TOBEY, of Boston, in the county of Suffolk, and State of Massachusetts, have invented a new and improved Scissors Sharpener, and I hereby declare that the following is a full and exact description thereof, reference being had to the accompanying drawings, and the letters of reference marked thereon, making a part of this specification, of which—

Figure 1 is a perspective view of the invention.

Figure 2 is an end view of ditto.

Figure 3 is a cross-section of ditto.

The letter A represents the block to which the sharpener is fastened; B, the sharpener; and C, the screw holding the sharpener fast to the block.

My invention consists in so fastening a section of a rectangular file, or piece of steel the surfaces of which are cut in the manner of a file, to a block of wood or metal, that by applying the scissors or shears with the hand the same are easily sharpened.

Fig. 1 in the drawings explains the invention. A is a block of wood, of any suitable kind, or the block may be composed of metal; it is rectangular in form, with its upper surface partially chipped off so as to allow the steel to sit squarely down upon the surface of the block, with one of its sides pressed against the shoulder made by chipping off part of the surface of the block. B is the sharpener, composed of steel, having all its sides cut in the manner of a file; when one side of the steel is worn by use, unscrew and change the side of the steel. C is a screw or any simple fastening to keep the steel in its place. In order to use the invention, take the block in one hand, or place it upon a bench or table, with the side having the screw downwards; take the scissors or shears in the other hand, holding the flat surface of the scissors to the surface of the block, and draw the edge of the scissors back and forth on the steel. The surface of the block on the side of the steel may be rectangular or otherwise, as may be most practicable. The invention is simple, cheap, and of practical utility. The cost of the article will be trifling, and one in a family will last for a long time for the purposes of scissors grinding or sharpening.

What I claim as my invention, and desire to secure by Letters Patent, is—

The combination and arrangement of the block A, the steel B, and the screw C, in such a way as to form a scissors sharpener, substantially in the manner and for the purpose set forth.

JAMES J. TOBEY.
